UNITED STATES PATENT OFFICE.

ERNEST H. FRIEDRICHES, OF NEW YORK, N. Y.

APPARATUS FOR THE APPLICATION OF PAINT OR COLORING MATERIAL TO ARTISTS' ACADEMY-BOARDS.

SPECIFICATION forming part of Letters Patent No. 287,530, dated October 30, 1883.

Application filed May 25, 1883. (No model.)

To all whom it may concern:

Be it known that I, ERNEST H. FRIEDRICHES, of the city, county, and State of New York, have invented a new and useful 5 Apparatus for the Application of Paint or Coloring Material in the Manufacture of Artists' Academy and Mill Boards.

In previously-known processes for the preparation of academy and mill boards the paint 10 has been applied to the binder-board either by a brush or a roller, and great difficulty has been experienced in producing a sufficiently smooth surface. This difficulty is overcome and a smooth and even surface is economically produced by my apparatus, of which the following is a full, clear, and exact description.

In the accompanying drawings, to which reference is made, Figure 1 represents a plan 20 view of my new apparatus. Fig. 2 is a vertical section of the same on the plane of the line *c c*, Fig. 1. Fig. 3 is a face view, and Fig. 4 a cross-section, of the wiper used by me.

A is a table having an even, level surface 25 of glass, steel, or marble or other substance, and quite flat, upon which the process is carried out. Preferably a slab, *S*, of glass is let into a depression formed in the top of this table.

B is a three-sided rectangular frame, which 30 may be attached to the table by a hinge at *b*. Fig. 2 shows the same table with the frame, with a sheet, *D*, of binder-board between the frame and the table in position for the application of the coloring material.

E is a scraper or wiper having a continuous blunt edge and with one side slightly convex, and of a suitable width to allow of its passing freely between the sides *d* and *e* of the frame *B*.

To prepare the academy or mill boards, a sheet of ordinary binder-board somewhat larger than the frame *B* is placed upon the table, and the frame is brought down evenly 45 upon it, as in Fig. 2, and is held firmly in position either by its own weight or by any suitable fastening. It will be seen that the

mill-board is held quite flat on the table. A suitable amount of paint or coloring material is then distributed upon the end of the sheet 50 which is nearest the cross-bar *f*. For the ordinary sheet—eighteen and one-half inches by twenty-four and one-half inches—I ordinarily put on about one-half pound of paint for the first coat. I then place the wiper upon the 55 sheet at the closed end of the frame in a vertical position, edge downward, with the convex side toward the open end of the frame, and move it rapidly in that position, with the paint before it, over the entire surface of the 60 sheet, between the sides of the frame, and off at the open end, where the superfluous paint not adhering to the board falls into a vessel for the purpose, the frame preventing it from flowing off at the sides. This process is re- 65 peated once or more, according to the smoothness of the finish desired and according to the evenness of the binder-board, an uneven or imperfect board requiring more coats than a more perfect one. Instead of moving the wiper, 70 the table may be moved, with the board *D*, under a stationary continuous wiper. The frame *B* is then lifted, and when the sheet has dried, the edges that were under the frame *B* are trimmed and it is ready for delivery; or, before trimming, the sheet may be reversed and a coating given to the other side, if desired.

It will be seen that if the frame *B* is used to hold the board *D* in place, the margin of the latter, where it is in contact with said frame, 80 will not be covered with the paint.

Having thus described my invention, what I claim as new, and desire to secure by Letters Patent, is—

In an apparatus for the preparation of 85 artists' academy and mill boards, the combination of the flat table *A* with the frame *B*, which is open at one end, and with the wiper or scraper *E*, for the purpose herein specified.

ERNEST H. FRIEDRICHES.
